UNITED STATES PATENT OFFICE.

WALTER LA FARY, OF HERNDON, IOWA, ASSIGNOR OF ONE-HALF TO L. M. SWINDLER,
OF YALE, IOWA.

COUPLING.

1,090,922.

Specification of Letters Patent. Patented Mar. 24, 1914.

Application filed December 28, 1912. Serial No. 739,090.

To all whom it may concern:

Be it known that I, WALTER LA FARY, a citizen of the United States, residing at Herndon, in the county of Guthrie and

5 State of Iowa, have invented certain new and useful Improvements in Couplers, of which the following is a specification, reference being had therein to the accompanying drawing.

10 This invention relates to air brake systems and has special reference to a novel form of coupling for the pipe lines of cars.

The principal object of the invention is to improve the general construction of devices of this character.

15 A second object of the invention is to provide an improved mechanism for opening and closing certain controlling valves in the pipe lines of cars when said pipe lines are coupled.

20 A third object of the invention is to provide means for automatically holding the controlling valves open in case the car accidentally becomes uncoupled.

25 With the above and other objects in view this invention consists in general of certain novel constructions, combinations and arrangements of parts, as will be hereinafter fully described, illustrated in the accompanying drawings, and specifically claimed.

30 In the accompanying drawings, like characters of reference indicate like parts in the several views, and Figure 1 is a side elevation, partly in section of the coupling means as applied to the frames of adjacent cars. Fig. 2 is a bottom plan view partly in section on the line 2-2, Fig. 1 of such an arrangement. Fig. 3 is a similar view showing a single car uncoupled and the valve closed. Fig. 4 is a side elevation of the single car as shown in Fig. 3. Fig. 5 is a detail section on the line 5-5, Fig. 3. Fig. 6 is a detail perspective of a certain suspension plate used herewith. Fig. 7 is a detail section of a certain guide casting used herewith.

35 In the present drawing showing one embodiment of the invention there is provided a car frame consisting of an end sill 10, side sills 11, and center sills 12. In connection with these sills there is provided on each car the usual draw bar 13 carrying a coupler head 14. Secured to each of the center sills 12 is an angularly bent plate 15

which depends from the respective sill and 55 between these plates are carried a pair of guide castings 16 in the form of U-shaped members having certain notches 17 and 18 at each end, one of the notches being preferably square while the other is round. One 60 of these castings is also provided with a recess 19 for purpose hereinafter to be described.

At 20 is indicated the train line of the respective car. Extending through the 65 openings formed by the notches 18 and 17 is a pipe 21 which is connected to the pipe 22. The forward end of this pipe is square as indicated at 23 so that movement of the pipe backward and forward through the 70 notches may be had without the pipe rotating with respect to the car.

On each of the pipes 21 is a collar 24 and between each collar 24 and the back end of the castings 16 is a coil spring 25 which normally urges the pipe outward. On the end of each pipe 21 there is provided a head 26 and the passage through the pipe is deflected to one side of each head as indicated at 27 and then turned inward toward the center 80 line of the head as shown at 28. Each head is cut away in such a manner as to form a beveled shoulder 29, the cut away portion extending to the vertical center plane of the respective head so that when two of these 85 heads are brought together the beveled end 30 of one will fit within the V-shaped notch made by the shoulder 29 and the face of the cut away portion. Furthermore, the parts are so proportioned that when the heads 90 are fitted together as shown in Fig. 2 the openings 28 will be in alinement. Adjacent each of these openings each head is provided with a seat 31 wherein is held a washer 32. Each of the heads 26 is furthermore provided with a valve 33 which is connected by means of a link 34 with a lever 35. This lever 35 is pivoted as at 36 between lugs 37 carried on the respective heads 26. The forward end of this lever is enlarged 100 to form a cam head 38 while the rear end is extended to form a tail 39 against which presses a spring 40 which normally rotates the cam head 38 inward toward the vertical central plane of the respective head 26.

105 Each of the heads 26 is provided with a cut off valve 41 which is normally kept closed. Each of the heads 26 is provided

with a lug 42 whereto is pivoted a lever 43 which is so arranged that when in one position the curved end 44 of this lever will lie between the head 26 and the respective lever 35. The other arm of the lever 43 is provided with a weight 45 which normally urges the curved end between the respective head 26 and the lever 35. Connected to the lever 43 is an operating lever 46.

- 10 In the operation of the device when the cars are uncoupled the parts are in the position shown in Fig. 3. When, however, the two cars come together for coupling, the beveled end 30 of each head 26 engages beneath the cam head 38 of the lever 35 of the opposite head, thus forcing said cam heads outward against the action of the springs 40. This opens the valves 33 and, at the same time, the two heads lock together 20 so as to bring the openings 28 into alignment and permit free communication between one pipe 20 and the pipe of the adjacent car. Meanwhile the weights 45 have caused the curved ends 44 of the levers 43 to slip beneath the respective levers 35. Furthermore, the springs 25 have yielded so that these parts will be tightly held together no matter what the position of the couplers 14.

It will be noted from Fig. 2 that the purpose of the pockets 19 is to permit the tails 39 of the respective levers 35 slipping into said pockets as indicated in Fig. 2.

If the cars become accidentally uncoupled the opening 28 will be opened to the atmosphere and the brakes will be set. If, it be desired to uncouple the cars purposely the train-man may, by proper manipulation of one or the other of the levers 46 move the respective end 44 from beneath the lever 35 thereby permitting the closing of the valve 33 controlled by said lever as the cars pull apart. It will be obvious that the train-man releases the lever 43 as soon as the train is apart so that when it is again coupled 45 the valve will open and be automatically held in open position against accidental uncoupling.

There has thus been provided a simple and efficient device of the kind described and 50 for the purpose specified.

Having thus described the invention, what is claimed as new, is:—

1. In a device of the kind described, a coupler head having an opening therethrough, 55 a valve controlling said opening, a lever controlling said valve, and means to automatically lock said lever when the valve is in open position.
2. In a device of the kind described, a coupler head having an opening therethrough, 60 a valve controlling said opening, a lever controlling said valve, means to automatically lock said lever when the valve is in open position, and a hand lever for throwing said 65 means to inoperative position.

3. In a device of the kind described, a coupler head having an air opening therethrough, a valve controlling said air opening, a lever connected to said valve and pivoted to said head, a cam head on said lever adapted to be acted on by a second coupler head to move the lever and open the valve, a spring normally urging said lever to close said valve, a safety lever pivoted to said coupler and adapted to have its end inserted between the coupler head and lever when the valve is open, and means to move said safety lever end from between the first-mentioned lever and coupler head.

4. In a device of the kind described, a coupler head having an air passage therethrough, said head being cut away at its forward end to provide a beveled shoulder, and a beveled end extending beyond said shoulder, said opening being extended at right angles to open through the face of the cut away portion, lugs on said coupler head, a lever pivoted between said lugs and having a cam head adapted to lie within the space formed by the cut away portion, a spring carried by said head and constantly urging the cam head into said space, a valve carried by said lever and controlling an air opening, a safety device adapted for automatic insertion between said lever and coupler head, 90 and manual means for moving said safety device from between said lever and coupler head.

5. In a device of the kind described, a coupler head having an air passage therethrough, said head being cut away at its forward end to provide a beveled shoulder, and a beveled end extending beyond said shoulder, said opening being extended at right angles to open through the face of the cut away portion, lugs on said coupler head, a lever pivoted between said lugs and having a cam head adapted to lie within the space formed by the cut away portion, springs carried by said head and constantly urging the cam head into said space, a valve carried by said lever and controlling an air opening, a safety device adapted for automatic insertion between said lever and coupler head, manual means for moving said safety device from between said lever and coupler head; a pair of depending plates secured to the car frame, a pair of guide castings having notches adapted to coincide with the castings positioned between said plates, 105 a pipe extending from the rear end of said head, a shoulder on said pipe, and a spring surrounding said pipe and bearing at one end against said shoulder and at the other end against said castings.

6. A device of the kind described comprising a coupler head having an opening therethrough, one end of the opening being in communication with a source of fluid supply, a lever pivotally connected to said head, 110

a valve carried by the lever for controlling the passage of fluid through the opening, means acting on the lever tending to cause the same to close the valve a holding device 5 for causing the lever to retain the valve open, and means for rendering the holding device inoperative.

In testimony whereof I hereunto affix my signature in presence of two witnesses.

WALTER LA FARY.
